UNITED STATES PATENT OFFICE.

PHILIP H. KLEIN, JR., OF NEW YORK, N. Y., ASSIGNOR TO BERGMANN & CO., OF SAME PLACE.

COMBINED GAS AND ELECTRIC-LIGHT FIXTURE.

SPECIFICATION forming part of Letters Patent No. 311,131, dated January 20, 1885.

Application filed April 2, 1884. (No model.)

To all whom it may concern:

Be it known that I, PHILIP H. KLEIN, Jr., of New York city, in the county and State of New York, have invented a certain new and useful Improvement in Combined Gas and Electric-Light Fixtures, of which the following is a specification.

The object of my invention is to produce an efficient construction of bracket, chandelier, and other form of fixture, designed for both gas and electric-light, wherein both lights will be arranged upon the same plane, and only one set of globes will be required.

In the accompanying drawings, forming a part hereof, Figure 1 is a side elevation of a bracket embodying my invention, the globe being in section; Figs. 2 and 3, an elevation and section, respectively, of the swiveled gas-arm tip used in the bracket; Fig. 4, a view, similar to Fig. 1, of a chandelier embodying the same features of construction as the bracket; Fig. 5, a similar view of a chandelier embodying a modified form of the invention; Fig. 6, a section through the swivel-joint of this last chandelier; and Fig. 7, an elevation and partial vertical section of a bracket or chandelier arm, showing the preferred method of arranging the gas and electric-light arms.

The invention is carried out by making the arm or arms for one lighting medium stationary, and arranging the arm or arms for the other medium, or a tip or tips thereon, for movement in a horizontal plane. The electric-lamp arms are preferably stationary, while the gas-arms have swiveled tips carrying burners, or the gas-arms themselves have a swiveled support and move in a horizontal plane.

With reference more particularly to Figs. 1, 2, and 3, A is an electric-lamp arm carrying on its end an electric-lamp socket, B, provided with circuit-controller *a*. The arm A also supports a globe, C. The electric lamp D is shown in dotted lines. When placed in the socket D, it rises in the center of the globe C. E is a gas-arm combined in the same bracket with arm A, and extending also to the globe C. This arm has a gas-cock, *b*. It rises above the electric-lamp socket B, and is provided with a horizontally-projecting tip, F, carrying an upright gas-burner, G, on its end. This tip F is swiveled upon the end of arm E, so that it

can be swung in a horizontal plane, its movement being limited by a pin, *c*. The swivel-joint H between E and F is also a gas-cock, it being open when F is swung to bring the burner G to the center of the globe, and closed when the burner is swung away from that position. This makes it impossible to throw the flame against the globe. When electric light is to be used, the gas-burner is swung aside and an electric lamp is placed in the socket B. Before using the gas it is necessary to remove the electric-lamp from the socket, and to swing the gas-burner to the center of the globe. These same features may be applied to chandeliers, as shown in Fig. 4.

The preferred method of arranging the gas and electric-light arms in a bracket or chandelier is shown in Fig. 7, the electric-light arm being the ornamental sleeve surrounding the gas-arm, and the wires being run through the space between this sleeve and the gas-pipe. A head, B', is employed to support the electric-lamp socket and the extension of the gas-pipe, as shown.

In Fig. 5 the gas-arms are mounted upon a swiveled support and swung in a horizontal plane. The chandelier is swiveled at the joint I, any suitable form of gas-swivel being used. The gas-arms E are supported on the lower turning part of the chandelier, and carry the globes C. The electric-lamp arms A are supported by the upper stationary part of the chandelier, and have sockets B, carrying downwardly-hanging electric lamps D. The globes C swing clear of the sockets B, as shown, but not of the lamps.

When the electric lamps are to be used, the gas-arms are swung so as to bring the lamps into the globes. Before swinging the arms the lamps or globes are removed, and are replaced after the proper position of the parts is obtained. When it is desired to use the gas, the gas-arms are swung to a position between the electric-lamp arms, the electric lamps or the globes being first removed from position.

It is evident that in either form of the invention the arrangement may be reversed and the electric-light portion of the structure made the swinging part, the conductors being connected at the swivel-joint in any of the ways used in jointed brackets for electric lamps.

The invention, in the form shown in Figs. 1, 2, 3, 4, and 7, can also be applied to swinging or jointed combination-brackets of any suitable construction—such, for instance, as that shown in Patent No. 293,553.

What I claim is—

1. In combined gas and electric-light fixtures, the combination, with a globe, of a gas-burner and an electric-lamp socket, both permanently attached to the fixture, one of said parts being located in the center of said globe, while the other is adjustable toward and away from the center of the globe, substantially as set forth.
- 15 2. In combined gas and electric-light fixtures, the combination of a gas-arm and an electric-lamp arm with a globe common to the gas-burner and the electric lamp, and means for swinging in a horizontal plane the part or parts conducting one lighting medium, substantially as set forth.
- 20 3. In combined gas and electric-light fixtures, the combination, with a stationary electric-lamp arm, of a gas-arm, a swivel-joint permitting the movement of the gas-arm or a part thereof toward and away from the electric lamp, and a globe common both to the gas-

burner and the electric lamp, substantially as set forth.

4. In a combined gas and electric-light fixture, the combination, with a globe, of an electric lamp stationary in said globe, and a swiveled gas-tip capable of being swung into and out of position for lighting in said globe, substantially as set forth. 35

5. In a combined gas and electric-light fixture, the combination, with a globe, of an electric lamp stationary in said globe, and a swiveled gas-tip capable of being swung into and out of position for lighting in said globe, said 40 swiveled gas-tip forming a gas-cock, substantially as set forth.

6. In combined gas and electric-light fixtures, the combination of gas and electric-light arms, located one within the other, with a 45 globe common both to the gas-burner and the electric lamp, and a swinging tip for one of the arms, substantially as set forth.

This specification signed and witnessed this 28th day of March, 1884.

PHILIP H. KLEIN, JR.

WM. H. MEADOWCROFT,

ALFRED W. KIDDLE.

Correction in Letters Patent No. 311,131.

It is hereby certified that in Letters Patent No. 311,131, granted January 20, 1885, upon the application of Philip H. Klein, Jr., of New York, New York, for an improvement in a "Combined Gas and Electric Light Fixture," an error appears requiring the following correction, viz: The grant should read that the said patent was assigned to *Bergmann and Company, its successors or assigns*, instead of "Bergmann & Co., their heirs or assigns;" and that the grant should be read with this correction therein to make it conform to the records pertaining to the case in the Patent Office.

Signed, countersigned, and sealed this 27th day of January, A. D. 1885.

[SEAL.]

M. L. JOSLYN,
Acting Secretary of the Interior.
